FIG. 1 is perspective view from the front left of an exterior
surface configuration of a vehicle front light. The drawings
and descriptions represent the right side embodiment. The
design also contemplates a mirror symmetrical embodiment
on the left side of the vehicle. The dash line included denotes
environment and is not part of the claimed design

FIG. 2 is a front elevation view thereof;

FIG. 3 is a left elevation view thereof; and,

FIG. 4 is a top view thereof.
